UNITED STATES PATENT OFFICE

LEWIS READING SMITH, OF ROME, GEORGIA.

COLLAPSIBLE CUP.

1,033,744.

Specification of Letters Patent. Patented July 23, 1912.

Application filed February 12, 1912. Serial No. 677,167.

To all whom it may concern:

Be it known that I, LEWIS R. SMITH, a citizen of the United States, residing at Rome, county of Floyd, State of Georgia, have invented certain new and useful Improvements in Collapsible Cups; and I do hereby declare the following to be a full, clear, and exact description of the invention, such as will enable others skilled in the art 10 to which it appertains to make and use the same.

This invention relates to certain improvements in collapsible drinking cups; and the objects and nature of the invention will be 15 readily understood by those skilled in the art in the light of the following explanation of the accompanying drawings illustrating what I now believe to be the preferred embodiment from among other formations and 20 arrangements within the spirit and scope of my invention.

The invention consists in certain novel features in construction and in combinations and arrangements as more fully and particularly described hereinafter.

Referring to the accompanying drawings:—Figure 1, is a perspective view of the cup distended. Fig. 2, is a vertical section thereof. Fig. 3, is a view showing the cup 30 collapsed. Fig. 4, is a view showing the same partially collapsed.

The cup is formed with a wall or body 1, composed of any suitable flexible or foldable water proof material. Paper paraffined or 35 otherwise treated to render the same water-proof, water proof fabric, rubber, and various other materials might be employed to form the wall of the cup.

The cup is provided with an annular top 40 stiff rim or ring 10, formed in any suitable manner and by any suitable material. This stiffening rim can be formed by rolling, folding or doubling the top edge of the material of the wall 1, and stiffening the same by 45 paraffin or other material, or said rim can be formed by a separate stiff ring around which the flexible material of the wall can be suitably secured. The bottom of the cup is also provided with a stiffening ring or 50 head to which the flexible material of the wall is suitably secured to form a water-tight joint. For instance, I show a stiff bottom head 11, to which the material of the wall is secured or clamped. The closed bottom 55 of the cup is preferably of reduced diameter with respect to the top rim of the

cup, so that when the cup is collapsed the wall 1, can fold on the bottom and within the rim into a small flat shape occupying so little space that the collapsed cup can be 60 easily carried on the person or in a pocket book, hand bag or the like.

The flexible material of the wall is preferably formed with vertical and diagonal fold lines *a*, so that the cup will collapse 65 and expand with a partial rotary or twisting movement, and whereby the wall of the cup when collapsed will be twisted so as to fold flat and evenly on the bottom wall and within the rim.

The cup is readily distended by grasping the rim and bottom and separating the same with a twisting motion. The cup can then be held by the rim and filled with liquid for drinking purposes. To prevent the cup 70 from collapsing or partially collapsing, when inclined to the mouth during the drinking operation and thus causing the liquid to spill over or flood the drinker, I provide a finger ring or hold 2, at the exterior of the lower end or bottom of the cup. This ring or finger hold is loose or pivoted 75 so that it can fold or swing to the cup bottom to rest flat thereagainst when the cup is collapsed. I show the ring 2, loosely pivoted to the center of the cup bottom by eye or fastening 20, and depending loosely from the cup bottom to receive the little finger 80 of the hand holding the cup for the purpose of maintaining the cup distended during the 85 drinking operation. When the cup is used for drinking purposes, the thumb and forefinger can grasp the top stiff rim of the cup and thus support the same while the liquid in the cup will ordinarily hold the cup distended when held in the vertical position. The little finger inserted in said ring or 90 other finger hold at the bottom of the cup will firmly hold the cup stretched and distended in the desired straight longitudinal 95 line when the cup is tilted from the vertical position.

It is evident that various changes, variations and modifications might be resorted to without departing from the spirit and scope of my invention and hence I do not wish to limit myself to the exact disclosure hereof.

What I claim is:—

1. A collapsible cup consisting of a top 110 supported rim, a stiff bottom portion, and a flexible foldable wall connecting the rim

and bottom portion and creased to fold inwardly with a relative rotary or twisting motion between the rim and bottom when the cup is collapsed into flat form, the lower end 5 of the cup provided with exterior means to be engaged by a finger of the hand supporting the cup by the top rim to maintain the cup wall against collapse and stretched in operative position between said rim and said 10 bottom portion when tilted for drinking purposes.

2. A collapsible cup having a top rim for supporting the cup and adapted to be grasped by the thumb and forefinger, and 15 provided with a flexible foldable wall adapted to fold flat to said rim and having a closed bottom provided with an exterior foldable finger ring adapted to receive a finger of the hand supporting said cup by the 20 rim and to hold said wall against collapse and stretched in operative form from said rim.

3. A collapsible cup consisting of a stiff 25 top supporting rim, a bottom having an exterior finger hold, and a flexible foldable

wall connecting the bottom and rim and creased to fold inwardly between the rim and bottom when the cup is collapsed into flat form, said cup adapted to be supported by the thumb and forefinger grasping said 30 rim and to be held against collapse and stretched in operative form by another finger engaging said finger hold.

4. A collapsible cup consisting of a top supporting rim and a flexible foldable wall 35 depending from said rim and adapted to collapse inwardly and fold thereto when the cup is collapsed into flat form and at its bottom provided with an exterior finger ring adapted to receive a finger of the hand 40 supporting the cup by the rim and to hold said wall against collapse and stretched in operative form from said rim when the cup is tilted.

In testimony whereof I affix my signature, in presence of two witnesses.

LEWIS READING SMITH.
